The ornamental design for a tilt base support for CRT terminal or the like, substantially as shown and described.

DESCRIPTION

FIG. 1 is a front perspective view of a tilt base support for CRT terminal or the like showing my new design, the terminal being shown in broken lines for illustrative purposes only;

FIG. 2 is a perspective view thereof on an enlarged scale;

FIG. 3 is a top plan view thereof on an enlarged scale;

FIG. 4 is a front view thereof on an enlarged scale;

FIG. 5 is a rear view thereof on an enlarged scale;

FIG. 6 is a side view thereof on an enlarged scale.
